Application September 26, 1939, Serial No. 296,610

4 Claims. (Cl. 250—27.5)

Our invention relates to a discharge tube having a cathode structure in which electrons are evaporated from a heated filament; and it is among the objects of our invention to provide improved means for supporting and tensioning the filament.

Another object is to provide a cathode structure embodying a filament tensioning spring disposed outside the intense heat zone in the tube to prevent heat from deteriorating the spring so that the life of the latter is preserved for maintaining a constant predetermined tension in the filament.

Further objects include the provision of improved means for mounting the grid and plate of a thermionic tube, and of means for cooling the plate supporting structure.

The invention possesses other objects and features of advantage, some of which, with the foregoing, will be set forth in the following description of our invention. It is to be understood that we do not limit ourselves to this disclosure of species of our invention, as we may adopt variant embodiments thereof within the scope of the claims.

Referring to the drawing:

Figure 1 is a side view, partly in section and partly in elevation, showing a thermionic tube embodying the improvements of our invention; and

Figure 2 is a detail sectional view of the cathode structure on larger scale.

In thermionic tubes having cathode structures comprising wire filaments a problem arises due to the fact that the filaments expand and warp when heated unless they are maintained under constant tension. Various arrangements of springs have been employed to tension the filaments, but experience has proven that the springs in past structures have rapidly deteriorated under the intense heat developed in the tubes. We have overcome this difficulty by providing a cathode structure in which the spring is disposed outside the intense heat zone in the tube, so that the spring maintains its resiliency throughout the life of the tube. Another problem in thermionic tubes is that of keeping the plate supporting structure reasonably cool. In our improved device the structure is designed to maintain the temperature of the parts within safe limits.

In terms of broad inclusion, the thermionic tube of our invention comprises an envelope enclosing a cathode structure including a filament and means for supporting it. A spring for ten-

sioning the filament is interposed in the supporting means, and the latter is designed to locate the spring outside the intense heat zone in the envelope. Improved means are also provided for mounting a grid and plate in the envelope; the plate mounting being particularly designed for cooling the supporting parts.

In greater detail, and referring to the drawing, the thermionic tube embodying our invention comprises a glass envelope 2 having a suitable base 3 with filament terminal prongs 4. A reentrant stem 6 is provided at the top of the envelope for the anode structure, and a stem 7 is arranged at the base of the envelope for the cathode structure.

The cathode preferably comprises a pair of hairpin filaments 8 of thoriated tungsten secured at their lower ends to cross bars 9 fastened to the upper ends of a pair of tungsten rods 11 projecting upwardly from a pinch 12 of stem 7. Suitable leads 13 are connected between the lower ends of these rods and the terminal prongs 4. The upper ends of the filaments are held by a cross arm 14 mounted on a centrally disposed supporting rod or standard 16 projecting upwardly from the stem 7.

Supporting arm 14 engages the bights of the filaments and is slidably mounted on standard 16 so that upward pressure on the arm tensions the filaments. A coil spring 17 of suitable material, such as tungsten, is disposed coaxially about the lower portions of the standard, well below the filament. This spring is compressed between a suitable stop and the lower end of a coaxial sleeve 18 which slidably embraces the standard and projects upwardly to bear against the underside of filament supporting arm 14. The ends of the spring are seated in cup-shaped pieces 19; and a clip 21 fastened to standard 16 forms the stop for the lower end of the spring. These parts as well as the sleeve 18 and arm 14 are preferably made of a formable heat resistant material, such as tantalum.

By this arrangement the spring 17 is disposed outside the intense heat zone adjacent the filament, and the spring is therefore not deteriorated by the heat generated in the tube. If desired, the spring may be lowered to rest on the stem 7, thus removing it still further from the heat zone. Ordinarily such distant spacing is not required however and the spring may safely be disposed further up along the standard, as shown in the drawing.

Grid 22 of our tube is disposed coaxially about the cathode structure and is supported by a ring

23 fastened to an angularly disposed conductive rod 24 of tungsten having its outer end sealed in a side wall of the envelope.

The anode structure comprises a cylindrical plate 26 arranged coaxially with the other elements and having radially disposed cooling vanes 27. This plate is supported by a plurality of depending tungsten rods 28 extending through pinches 29 of upper stem 6. Reentrant stem 6 forms a cavity 32 opening out to the atmosphere for ventilation, and the upper ends of rods 28 are connected to enlarged risers 33 of a good heat conducting material such as copper to rapidly convey heat from the stem structure. These risers are connected to a terminal button 34 also 15 preferably of copper.

In larger tubes, where the plate supporting rods are quite heavy, heat conduction from the plate may be retarded by reducing the cross-section of the rods adjacent the plate, as by tapering their lower ends 36. This permits the use of sufficiently heavy rods for rigidity, yet tends to thermally isolate the plate.

For further cooling the stem structure we provide an aperture 37 in terminal button 34 and 25 make connection with a suitable blower through a flexible duct 38 for directing a stream of cooling fluid or air into the cavity of the stem. By employing a flexible duct of electrical conducting material this duct may also serve as the plate 30 lead. If desired, cooling fins may be provided on terminal button 34, either formed as an integral part of the button or on a separate sleeve encircling the button.

Another cooling feature in our tube, associated with the cathode structure, is the projection of the lower end of standard 16 into the air space of hollow stem 7. The standard or rod 16 thus also functions as a heat conducting member for

conveying heat from the cathode supporting structure to a point outside the envelope. It is also to be noted that spring 17 is disposed adjacent the lower or heat dissipating end of the standard, so that the spring gets full benefit of the cooling.

We claim:

1. In a thermionic tube, a cathode structure comprising a filament, a standard, a filament supporting arm slidable on the standard, a sleeve embracing the standard and bearing at one end against said arm, and a spring surrounding the standard and bearing against the other end of the sleeve for tensioning the filament.

2. In a thermionic tube, a cathode structure comprising a hairpin filament, a standard, a supporting arm slidable on the standard and engaging the bight of the filament, a sleeve embracing the standard and bearing at one end against said arm, and a spring encircling the standard and bearing against the other end of the sleeve for tensioning the filament.

3. In a thermionic tube, a cathode structure comprising a hairpin filament, a standard projecting upwardly from the base of the tube, a supporting arm slidable on the standard and engaging the bight of the filament, a sleeve embracing the standard and extending downwardly from said arm, and a spring encircling the standard and bearing against the lower end of the sleeve for tensioning the filament.

4. In a thermionic tube, a cathode structure comprising a filament, a filament engaging element, a standard, a compression member slidable along said standard and bearing against said element, and a spring bearing against said member for tensioning the filament.

WILLIAM W. EITEL.
JACK A. McCULLOUGH.
